UNITED STATES PATENT OFFICE.

HORACE B. MURDOCK, OF DETROIT, MICHIGAN.

CASKET-LOWERING DEVICE.

SPECIFICATION forming part of Letters Patent No. 703,949, dated July 1, 1902.

Application filed October 16, 1901. Serial No. 78,856. (No model.)

To all whom it may concern:

Be it known that I, HORACE B. MURDOCK, a citizen of the United States, residing at Detroit, in the county of Wayne and State of Michigan, have invented certain new and useful Improvements in Casket-Lowering Devices; and I do hereby declare the following to be a full, clear, and exact description of the invention, such as will enable others skilled

in the art to which it appertains to make and use the same.

My invention relates to improvements in casket-lowering devices, and has for its object to provide a simple and efficient apparatus for lowering caskets into graves, adapted to lessen the possibility of the casket being violently thrown into the grave, owing to the attendants from any cause allowing the same to get away from their control.

With this object in view my invention consists in the construction and combination of parts, as hereinafter described, and set forth in the claims.

Referring to the drawings, in which like letters represent similar parts in the several views, Figure 1 is a plan view, partly in section, of my improved device. Fig. 2 is an end elevation of the same, partly in section and showing the casket in position. Fig. 3 is

a section taken on the line 3 3 of Fig. 1. Fig 4 is a side elevation of one of the supporting-legs. Fig. 5 is a section taken on the line 5 5 of Fig. 1. Fig. 6 is a plan view of the automatic device for releasing the ropes. Fig. 7 is a side elevation of same, and Fig. 8 is a perspective view of the brake or speed-governing device.

A is a hollow frame or casing having suitable reinforced portions A', and in one end 40 of this frame I provide an enlarged chamber B, in which are suitably mounted the drums C C' on the shafts c c'. The drums C C' are provided at one of their ends with the enlarged annular casing D D' and the gear-wheels E E', adapted to mesh with each other.

The drum C is mounted fast on the shaft c, which passes through the hollow shoulder b, formed integral with the chamber B.

50 The annular casing D contains a coiled

spring d, secured at one end to the inside of the casing and at its other end to the hollow shoulder b, as shown at Fig. 2.

The drum C' is loosely mounted on the shaft c', and the shaft c' is provided with the screw-threaded portion c², as shown in Fig. 1. Both the shafts c and c' are provided with squared ends to receive a key or operating-crank c⁰.

The annular casing D' contains a pair of 60 semicylindrical clutch-plates d', adapted to frictionally engage the inside wall of the casing. Between these clutch-plates, adapted to be moved longitudinally thereof and supported by the lugs f, is the plate F, provided 65 with the wedge-shaped ends f', most clearly shown in Fig. 8. This plate is internally screw-threaded centrally to engage the screw-threads c² on the shaft c'.

The frame A contains the grooved guide-pulleys G G', H H', and I I' for the ropes J and J', one of which ropes J' is shown crossed hatched for clearer illustration. These pulleys are mounted at suitable angles for properly guiding the ropes, as clearly illustrated 70 in Figs. 1, 2, 3, and 5, and it will of course be understood that similar sets of pulleys 75 will be provided at the opposite side of the frame A.

The frame A is supported by the detachable 80 legs a, provided with the hooked ends a' and projecting lug a². (Illustrated in Fig. 4.) The hooked ends a' are adapted to engage a rod a⁰, disposed longitudinally of the central portion of the frame A, and the leg being turned 85 a quarter-revolution the lugs a² engage the sides of the frame, as shown in Figs. 2, 3, and 4.

In order to release the ropes J and J' after the casket has been lowered, I provide an automatic device K of substantially the construction shown in Figs. 6 and 7. To one end 90 of each of the ropes is secured the U-shaped member L, provided with the transverse rod l. To the other end of the rope is secured the 95 member M, provided with the hooked end m, adapted to engage the transverse rod l. The member M is provided with flat springs N, adapted to engage the sides of the U-shaped member L.

The operation of the device is as follows: The ends of the two ropes being secured and the ropes drawn taut for holding the members of the locking device K in engagement, the 5 ropes are then ready to receive the casket. By turning the shaft c' the wedge-plate F is moved along the shaft, and, engaging between the clutch members $d' d'$, either forces said members apart, increasing the friction between the 10 clutch-plates and the inner wall of the casing D', or by reversing the direction of rotation of the shaft reduces the frictional contact between said clutch members and the casing, and this braking mechanism can thus be so 15 adjusted as to regulate the speed of descent of the casket. The operating-handle c^o is generally placed on the shaft c and is controlled by an attendant; but it is obvious that the frictional contact between the clutch-plates 20 $d' d'$ and the inner wall of the casing D' can be so regulated as to control the descent of the casket automatically. The casket having reached the bottom of the grave, the ropes are slackened, and the spring N, operating 25 upon the member L of the locking device K, will press said member L downwardly and throw the rod l out of engagement with the hook m of the member M, thus releasing the 30 ends of the ropes, and the shaft c' being rotated to sufficiently diminish the friction between the clutches $d' d'$ and the casing D' the coil-spring d , now under tension, will rotate the drum C for winding up the ropes. Thus 35 it will be seen that by my invention I do away with the necessity of the casket being actually handled by the cemetery attendants, thus permitting the body-bearers, generally friends of the deceased, to be the ones to deposit the body at its final resting-place, which, 40 it will be observed, is a much more respectful ceremony, obviating the indifferent handling which not infrequently occurs by the methods now in vogue.

Having thus described my invention, what 45 I claim, and desire to secure by Letters Patent of the United States, is—

1. In a casket-lowering device, the combination of a spring-operated drum, a second drum operatively connected to said first drum, ropes 50 carried by said drums, and means for regulating the speed of said drums.

2. In a casket-lowering device, the combination with a spring-operated drum, a second drum operatively connected to said first drum, 55 a friction-clutch engaging said second drum

for regulating the speed of said drums, and ropes carried by said drums.

3. In a casket-lowering device, the combination with the frame, of a hollow chamber formed in said frame, a pair of shafts revolvably mounted in said hollow chamber, a spring-operated drum secured fast to one of said shafts, a second drum operatively connected to said first drum loosely mounted on the other of said shafts, ropes carried by said drums, and means engaging said second drum for regulating the speed of said drums.

4. In a casket-lowering device, the combination with the frame, of a hollow chamber formed in said frame, a pair of shafts revolvably mounted in said hollow chamber, a drum secured fast to one of said shafts, a second drum, operatively connected with said first drum, loosely mounted on the other of said shafts, a wedge-plate mounted on said 70 second shaft and operative longitudinally thereof, clutches in said second drum, engaging said wedge-plate, means for operating said wedge-plate for regulating the speed of said drums, and ropes carried by said drums. 75

5. In a casket-lowering device, the combination with the frame, of a pair of revoluble drums, provided with an enlarged annular casing at one end thereof, mounted in said frame, a coiled spring inclosed in the casing 80 of one of said drums, secured at its ends to said casing and frame, a clutch mechanism in the annular casing of said other drum, for controlling the speed of said drums, and ropes carried by said drums. 90

6. In a casket-lowering device, the combination with the hollow frame, of an enlarged chamber formed in said frame, a pair of shafts revolvably mounted in said enlarged chamber, a drum secured fast to one of said shafts, a second drum operatively connected with said first drum, loosely mounted on the other of said shafts, screw-threads on said second shaft, a wedge-plate mounted on said second shaft, 95 engaging said screw-threads, clutches in said second drum, engaging said wedge-plate, pulleys suitably disposed in said hollow frame, and ropes reeving over said pulleys and connected to said drums.

In testimony whereof I affix my signature 100 in presence of two witnesses.

HORACE B. MURDOCK.
